TRANSVAAL.

MANTLE FOR CRUSHING-HEADS OF GYRATORY ROCK-CRUSHERS AND THE LIKE.

1,066,277.

Specification of Letters Patent.

Patented July 1, 1913.

Application filed October 31, 1910. Serial No. 589,933.

To all whom it may concern:

Be it known that we, DAVID GAVINE HUNTER and THOMAS GEORGE MURTON, both subjects of the King of Great Britain, and residents of Simmer and Jack, respectively, near Germiston, Transvaal, have invented certain new and useful Improvements in Mantles for the Crushing-Heads of Gyratory Rock-Crushers and the Like, of which the following is a specification.

This invention relates to gyratory rock, ore, or stone breakers or crushers, such for example, as the "Gates" gyratory rock and ore breaker. In this type of breaker the crushing is accomplished by a conical crushing head or a conical head center piece or core covered with a renewable mantle, said center piece or core being attached to or constricted integral with a usually vertical shaft by which the crushing head has a gyratory motion imparted to it inside a suitably constructed basin or receptacle into which the rock or like material to be crushed is introduced. In gyratory crushers of this class, the conical head or mantle wears to the greatest extent near the lower end, or at or near the part of largest diameter. After the head or mantle has become worn at this point to a considerable extent, it is now necessary to renew the entire head or mantle even though the upper portion thereof has only been but very slightly worn. Obviously this has entailed considerable waste of material usually of an expensive kind.

The object of our invention is to obviate this waste, and thereby effect a material reduction in maintenance costs or the expense of keeping such machines in good running order.

It consists essentially in making the conical head or mantle in a plurality of parts or sections, so that when the part or section or parts or sections which are subjected to the greatest amount of wear are sufficiently worn out it is only necessary to renew such worn out part or section or parts or sections, the remaining part or section or parts or sections being adapted to be fitted to a new part or section or parts or sections to replace that part or section or those parts or sections which have been removed.

The invention will now be described by aid of the accompanying drawing wherein—

Figure 1 represents a crushing head and a portion of its shaft in elevation constructed according to our invention, and Fig. 2 is a sectional elevation of the crushing head with the shaft in elevation.

1 represents the shaft to which a gyratory motion is imparted in any ordinary or suitable manner. The shaft 1, as usual, is constructed with a conical or tapering portion 2 upon which the crushing head center piece or core 3 is positioned. The center piece or core 3 is shown secured to the shaft in the usual manner by means of keys 4, preferably of zinc (which is reduced to a molten state, and in that condition poured into the key seats) and ring nuts 5, 6 (the upper one of which 6 operates as a check nut) screwed on to reduced portions of the shaft above the conical or tapering portion 2.

In the particular construction illustrated in the drawing the mantle is shown constructed in halves or comprising two parts 7 or sections of substantially equal length, an upper part or section 7, and a lower part or section 8. The halves 7, 8 are constructed with automatic locking means, shown consisting of interlocking projections 9, 10 formed at two diametrically opposite points in the mantle. The interlocking projections 9, 10 are shown formed by severing or dividing the halves, parts, or sections 7, 8 by two parallel planes 11, 12, preferably inclined to the longitudinal axis of the crushing head and mantle. The steps formed between the inner ends of the planes 11, 12 at opposite sides of the mantle are rounded and recessed to form the curved interlocking projections 9, 10. Either or both of the halves or sections 7, 8 may be fixed to the head center 3. In the drawing the part or section 8 is shown fixed to the head center 3 in a known manner, by providing it, at the lower end on the inside, with lugs 13, 14 which are adapted to pass through slots 15, 16 in the head center, and to engage spiral surfaces 17, 18 provided on the lower end of the head center. The partial rotation of the mantle 7, 8 when the lugs 13, 14 are in engagement with the spiral sur-

faces 17, 18 draws the mantle firmly down on the head center 3. Obviously instead of or in addition to fixing the lower section 8 to the head center 3, the upper section 7 may also be fixed to it in any convenient manner. The projections 9, 10 by locking in both directions prevent any movement of the upper section 7 relative to the lower section 8 when the gyratory motion is imparted to the shaft 1 and crushing head.

Although we show the mantle constructed in two sections it is to be understood that it may consist of any desired number of sections, and the several sections be connected by the interlocking projections (as 9, 10) in the manner above described.

In arranging the two-part or sectional mantle on the head center 3 the sections 7, 8 are first placed together so that the projections 9, 10 interlock and are then placed in position on the head center 3 and secured by twisting the mantle to cause lugs 13, 14 to engage the spiral surfaces 17, 18.

What we claim as our invention and desire to protect by Letters Patent is:—

1. In rock crushers, a crushing head center and a mantle therefor, said mantle comprising a plurality of sections, the adjacent ends of the sections having interlocking projections for preventing axial separation of said members.

2. In a rock crusher, a crushing head center and a mantle therefor, said mantle comprising at least two sections coacting at a plurality of plane surfaces on each section all lying in parallel planes inclined to the longitudinal axis of the mantle and having interlocking projections and recesses connecting said surfaces.

3. In a rock crusher, a conical head center and a conical mantle therefor, said mantle comprising at least two sections coacting at a plurality of plane surfaces on each section all lying in parallel planes inclined to the longitudinal axis of the mantle and having interlocking projections and recesses connecting said surfaces.

4. In a rock crusher, a sectional crushing head, the sections of the head having portions automatically interlocking upon relative rotary adjustment of the sections whereby axial separation of the sections of the head is prevented.

5. In a rock crusher, a crushing head center, and a sectional mantle on said head center, the sections of said mantle having interlocking portions and one of said sections being free to automatically turn on said head center to interlock said portions, whereby axial separation of the mantle sections on the head center is prevented.

6. In a rock crusher, a sectional crushing head, each section of the head having a right and a left hand interlocking portion

one of which automatically interlocks with 65 its corresponding portion upon relative rotary adjustment of the sections in one direction and the other of which automatically interlocks with its corresponding portion upon relative rotary adjustment of the 70 sections in the opposite direction whereby axial separation of the sections of the head is prevented.

7. In a rock crusher, a crushing head center, and a sectional mantle on said head center, each of the sections of said mantle having a right and a left hand interlocking portion, one of which interlocks with its corresponding portion upon relative rotary adjustment of the sections in one direction and 75 the other of which interlocks with its corresponding portion upon relative rotary adjustment of the section in the opposite direction whereby axial separation of the section of the mantle is prevented. 85

8. In a rock crusher, a sectional crushing head comprising at least two sections coacting at a plurality of plane surfaces on each section, all of said planes being parallel and inclined to the longitudinal axis of the head 90 and said sections having interlocking projections and recesses connecting said surfaces.

9. In a rock crusher, a tapered central portion, and two sections of crusher head 95 on said central portion, one of said sections being locked to said central portion and the other being freely rotatable thereon until the same is tight on said central portion and both sections being formed with coacting 100 cam surfaces inclined to the axis of said sections.

10. In rock crushers, a crushing head center and a mantle therefor, said mantle comprising a plurality of sections formed by 105 separating the sections by two parallel planes and providing the steps thereby formed at two opposite sides of the mantle with interlocking projections and recesses.

11. In rock crushers, a conical crushing 110 head center and a conical mantle therefor, said mantle comprising a plurality of sections, the joints between the sections being formed by two parallel planes and forming the steps at the two opposite sides of the 115 mantle with interlocking projections and recesses.

12. In a rock crusher, a sectional crushing head comprising at least two sections, having coacting cam surfaces formed thereon 120 respectively facing toward their carrying sections.

13. In a rock crusher, a crushing head center and a sectional mantle therefor comprising at least two sections, having cam surfaces formed thereon respectively facing toward their carrying sections. 125

14. In a rock crusher, a tapered head center

ter and a sectional mantle on said head center, one of the sections being locked to said head center and the other being freely rotatable thereon until the same is tight on said head center and both sections being formed with coacting cam surfaces inclined to the axis of said sections.

5 In testimony whereof we have signed our

names to this specification in the presence of two subscribing witnesses.
